UNITED STATES PATENT OFFICE.

EVERETT B. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed October 8, 1924. Serial No. 742,405.

My invention relates to internal combustion engines of the two stroke cycle type, the principal objects of my invention being to generally improve upon and simplify the construction of the existing forms of two stroke cycle internal combustion engine; to provide an engine having four combustion cylinders arranged in a row parallel with the axis of the crank shaft, said four combustion cylinders being arranged in pairs with the head ends of the members of each pair connected by a common clearance chamber; to combine with the four cylinders a pair of gaseous fuel pumping cylinders, the axes of which pumping cylinders are disposed at an angle relative to the axes of the combustion cylinders; to arrange the pumping cylinders in transverse alignment with the inner members of the row of four combustion cylinders; to provide the engine thus constructed with a two throw crank shaft, the throws or cranks of which are arranged diametrically opposite to each other; to connect the pistons within each pair of combustion cylinders to one of the throws of the crank shaft; to connect the pistons within the pumping cylinders to the respective throws of the crank shaft; and to provide each throw or crank of said crank shaft with a counterbalancing member that is disposed between the connecting rods that are connected to said crank or throw.

With the foregoing and other objects in view, my invention consists in the features of construction and combination and arrangement of parts hereinafter more fully described and claimed, reference being had to the accompanying drawings, is which—

Figure 1 is a top plan view of an internal combustion engine of my improved construction;

Figure 2 is a vertical cross section taken on the line 2—2 of Figure 1;

Figure 3 is a vertical section taken approximately on the line 3—3 of Figure 2.

Referring by numerals to the accompanying drawings, which illustrate a practical embodiment of my invention, 10 designates a cylinder block in which are formed four combustion chambers 11, 12, 13 and 14. The axes of these cylinders are arranged parallel with each other and the four cylinders are arranged in pairs with the cylinders 11 and

12 constituting one pair and cylinders 13 and 14 the other pair.

The head end of block 10 is closed by a head block 15, and formed in the under side thereof are shallow pockets or chambers 16 and 17, said chamber 16 connecting the head ends of combustion chambers 11 and 12 and providing a common clearance compression and ignition chamber therefor. In a similar manner, chamber 17 connects the head ends of combustion chambers 13 and 14 and provides a common clearance compression and ignition chamber therefor. Pistons 18 and 19 are arranged for operation, respectively, in chambers 11 and 12, and similar pistons 20 and 21 are arranged for operation, respectively, in chambers 13 and 14. Arranged in head 15 and preferably at points directly above the chambers 12 and 13 are ignition devices, such as spark plugs, 22, and the inner ends of the electrodes thereof project into the common clearance chambers 16 and 17.

Arranged below cylinder block 10 is a crank case 23 provided with suitably located bearings 24 for a crank shaft 25, the latter having two throws 26 and 27 that are disposed diametrically opposite to each other or 180° apart. Pistons 18 and 19 are connected, respectively, by suitable connecting rods 28 and 29 to crank 26, and in like manner, pistons 20 and 21 are connected, respectively, by connecting rods 30 and 31 to crank 27. Connected to the central portion of crank 26 and between the corresponding ends of connecting rods 28 and 29 is a counterbalancing member 32, and connected to the central portion of crank 27 between the corresponding ends of connecting rods 30 and 31 is a similar counterbalancing member 33. Arranged above crank case 23 and angularly disposed with respect to the row of combustion cylinders in block 10 is a block 34 in which are formed two pumping chambers, such as 35, the axes of which are parallel with each other, and these pumping cylinders are disposed so that their axes are respectively in transverse alignment with the axes of the combustion chambers 12 and 13.

I prefer to construct the blocks 10 and 34 so that the axes of all of the chambers therein intersect the axis of crank shaft 25. Ar-

ranged for operation within the pumping chambers 35 are gaseous fuel pumping pistons 36, and the latter are connected by suitable connecting rods, such as 37, to 5 cranks 26 and 27.

As a result of the arrangement of the pumping cylinders with relation to the combustion cylinders 12 and 13, the connecting rod from one of the gaseous fuel pumping 10 pistons is connected to crank 26 immediately adjacent to connecting rod 29, and to accomplish this connection the lower end of the connecting rod from the pump piston is preferably provided with a yoke, such as 38, 15 that engages crank throw 26 to the side of the lower end of connecting rod 29. In like manner, the lower end of the connecting rod from the piston in the other pumping cylinder is provided with a yoke, such as 39, 20 that engages crank 27 immediately to the side of the lower end of connecting rod 30. I prefer to arrange the main bearings 24 for the crank shaft so that there is a bearing at each end of each crank throw, and as a 25 result of such arrangement and the provision of the counterbalancing weights 32 and 33 the crank shaft is balanced so as to minimize vibration during engine operation.

The chambers within the gaseous fuel pumping cylinders are provided with suitably located gaseous fuel inlet ports, such as 40, that are connected to a suitable source of gaseous fuel supply, such as a carburetor, and the upper ends of the chambers within 30 said pumping cylinders are connected by suitable cross ducts 41 to the combustion chambers 12 and 13. These transfer ducts 41 are crossed between the pumping and combustion cylinders in order that the 35 pumping cylinder that is in transverse alignment with combustion cylinder 12 functions for the delivery of compressed gaseous fuel into combustion chamber 13, and the pumping cylinder 34 that is in transverse alignment with combustion cylinder 13 functions for the delivery of precompressed gaseous fuel into combustion chamber 12. The gaseous fuel inlet ports 40 and the precompressed gaseous fuel inlet ports into the 40 combustion cylinders 12 and 13 are located so that they are uncovered and open only when the corresponding pistons are at the lower or outer ends of their stroke. Combustion chambers 11 and 14 are provided with exhaust ports 42 that are located so that they are uncovered and open only when pistons 18 and 21 are at the lower or outer ends of their stroke.

In the operation of my improved engine, 45 the diametrically opposite arrangement of cranks 26 and 27 and the connections from the pistons in the pumping cylinders to said cranks are such that the two sets of pistons move simultaneously but in opposition or in 50 opposite directions to each other, and by the

cross-over arrangement of the ducts 41 each pumping piston on its upward stroke compresses gaseous fuel in the upper portion of its chamber and the duct leading therefrom, and when the pistons in the combustion 55 chamber to which the respective duct is connected passes low center and uncovers the gaseous fuel inlet ports to which said duct leads the compressed gaseous fuel charge is admitted to the corresponding combustion 60 cylinder and passes upwardly therethrough, thence through the corresponding common clearance chamber, and thence downward through the other combustion chamber of the pair, thus driving before it the products of combustion resulting from the previously 65 ignited charge, and the greater portion of said products of combustion will be expelled through the corresponding exhaust ports 42.

On the succeeding upward or inward stroke of the pistons within the connected combustion chambers, the gaseous fuel charge admitted as just described will be compressed in the corresponding common clearance chamber until the pistons in the 70 combustion chambers pass high center, at which time the compressed gaseous fuel charge will be ignited by a spark produced between the terminals of the corresponding 75 spark plug. The expansion following combustion of the compressed gaseous fuel charge will drive the pistons downward on their power stroke, and as the piston in each pumping cylinder is connected to the same 80 crank with a pair of the pistons in the combustion cylinders, each pumping piston will operate simultaneously with the pair of combustion cylinder pistons with which it is associated, but owing to the crossed ducts 85 41 the gaseous fuel pumped by each pumping piston will be transferred to the other pair of combustion cylinders, while the pistons 90 therein are passing low center and while the transfer inlet ports are open.

The counterbalancing weights 32 and 33 are disposed centrally on the cranks 26 and 27 between the piston rods that are connected thereto, and, consequently, a perfectly balanced rotary mass is provided, thus minimizing the development of vibration in the 95 crank shaft and associated parts, while the engine is in operation.

It will be understood that various changes may be made in the form, size and construction of my improved two stroke cycle internal combustion engine without departing 100 from the spirit of my invention, the scope of which is set forth in the appended claims.

I claim as my invention:

1. In a two stroke cycle internal combustion engine, a series of four combustion cylinders arranged in a row, said four cylinders being arranged in two pairs with the head ends of the members of each pair connected by a common clearance chamber a 105 110 115 120 125 130

- pair of cylinders functioning for the pumping of gaseous fuel that is delivered to said combustion cylinders, said gaseous fuel pumping cylinders being disposed at an angle relative to the plane occupied by the row of combustion cylinders, the two gaseous fuel pumping cylinders being disposed in transverse alignment with the inner two members of the row of combustion cylinders, pistons arranged for operation within all of said cylinders, a crank shaft having two crank throws that are arranged 180° apart, and connections from the pistons in each pair of combustion cylinders and from the pistons in one of the gaseous fuel pumping cylinders to each crank throw of the crank shaft.
2. In a two stroke cycle internal combustion engine, a series of four combustion cylinders arranged in a row, said four cylinders being arranged in two pairs with the head ends of the members of each pair connected by a common clearance chamber, a pair of cylinders functioning for the pumping of gaseous fuel that is delivered to said combustion cylinders, said gaseous fuel pumping cylinders being disposed at an angle relative to the plane occupied by the row of combustion cylinders, the two gaseous fuel pumping cylinders being disposed in transverse alignment with the two inner two members of the row of combustion cylinders, pistons arranged for operation within all of said cylinders, a crank shaft having two crank throws that are arranged 180° apart, connections from the pistons in each pair of combustion cylinders and from the piston in one of the gaseous fuel pumping cylinders to each crank throw of the crank shaft, and a counterbalancing member centrally arranged on each crank throw of the crank shaft, between the piston connections thereto.
3. In a two stroke cycle internal combustion engine, a series of four combustion cylinders disposed in a row with said four cylinders arranged in pairs and the head ends of the members of each pair connected by a common clearance chamber, a pair of gaseous fuel pumping cylinders, the members of which are in transverse alignment with the two inner combustion cylinders of the row, a crank shaft having two crank throws that are arranged diametrically opposite to each other, pistons arranged for operation within all of the cylinders, and connections from the pistons in each pair of combustion cylinders and the piston in one of the pumping cylinders to each throw of the crank shaft.
4. In a two stroke cycle internal combustion engine, a series of four combustion cylinders disposed in a row with said four cylinders arranged in pairs and the head ends of the members of each pair connected by
- a common clearance chamber, a pair of gaseous fuel pumping cylinders, the members of which are in transverse alignment with the two inner combustion cylinders of the row, a crank shaft having two crank throws that are arranged diametrically opposite to each other, pistons arranged for operation within all of the cylinders, connections for the pistons in each pair of combustion cylinders and the piston in one of the pumping cylinders to each throw of the crank shaft, and counterbalancing means carried by each crank throw of the crank shaft between the piston connections thereto.
5. In a two stroke cycle internal combustion engine, a series of four combustion cylinders arranged in a row, a pair of gaseous fuel pumping cylinders being offset from the row of combustion cylinders and occupying positions in transverse alignment with the two inner cylinders of said row of combustion cylinders, gaseous fuel ducts arranged between each pumping and one member of the row of combustion cylinders, a crank shaft having two rows that are arranged diametrically opposite to each other, pistons arranged for operation within said combustion and pumping cylinders, and connections from the pistons in each pair of combustion cylinders and the piston in one of the pumping cylinders to each crank throw of the crank shaft.
6. In a two stroke cycle internal combustion engine, a series of four combustion cylinders arranged in a row, a pair of gaseous fuel pumping cylinders, said pumping cylinders being offsets from the row of combustion cylinders and occupying positions in transverse alignment with the two inner cylinders of said row of combustion cylinders, gaseous fuel ducts arranged between each pumping cylinder and one member of the row of combustion cylinders, a crank shaft having two crank throws that are arranged diametrically opposite to each other, pistons arranged for operation within said combustion and pumping cylinders, connections from the pistons in each pair of combustion cylinders and the piston in one of the pumping cylinders to each crank throw of the crank shaft, and counterbalancing members arranged on the throws of the crank shaft between the piston connections thereto.
7. In an internal combustion engine, a two stroke cycle internal combustion unit of six cylinders, four of which are disposed in a row and functioning as combustion cylinders, the other two cylinders of the unit being arranged in transverse alignment respectively, with the two inner cylinders of the row of four combustion cylinders and functioning for the pumping of gaseous fuel to the combustion cylinders, a crank

shaft having two crank throws, pistons arranged for operation within all of the combustion and pumping cylinders, the piston within the second cylinder from either end 5 of the row of four combustion cylinders and the piston within the corresponding transversely aligned pumping cylinder being directly connected to the same crank throw of the crank shaft and the piston within the 10 first cylinder from each end of the row of combustion cylinders having a separate connection to the corresponding crank throw of the crank shaft.

8. In an internal combustion engine, a 15 two stroke cycle internal combustion unit of six cylinders, four of which are disposed in a row and functioning as combustion cylinders, the other two cylinders of the unit being arranged in transverse alignment respectively, with the two inner cylinders of 20 the row of four combustion cylinders and functioning for the pumping of gaseous

fuel to the combustion cylinders, a crank shaft having two crank throws, pistons arranged for operation within all of the combustion and pumping cylinders, the piston within the second cylinder from either end 25 of the row of four combustion cylinders and the piston within the corresponding transversely aligned pumping cylinder being directly connected to the same crank throw of the crank shaft and the piston within the first cylinder from each end of the row of combustion cylinders having a separate connection to the corresponding crank throw of 30 the crank shaft and a counterweight connected to each crank throw between the connection to the piston in the first cylinder in the row of four combustion cylinders and the connections to the piston in the second cylinder in the row and the piston in the transversely aligned pumping cylinder.

In testimony whereof I affix my signature.
EVERETT R. BURTNETT.
